UNITED STATES PATENT OFFICE.

RICHARD SCHULZ, OF HERNE, GERMANY.

CLUTCH MECHANISM FOR MINE CAGES OR LIFTS.

SPECIFICATION forming part of Letters Patent No. 653,940, dated July 17, 1900.

Application filed January 16, 1900. Serial No. 1,618. (No model.)

To all whom it may concern:

Be it known that I, RICHARD SCHULZ, miner, a subject of the Emperor of Germany, and a resident of Bahnhofstrasse 19¹, Herne, in the 5 Province of Westphalia and Empire of Germany, have invented certain new and useful Improvements in Clutch Mechanisms for Mine Cages or Lifts, of which the following is a full, clear, and exact description.

10 My invention relates to improvements in safety devices for mine cages and lifts employed for arresting the descent of the mine cage or lift when the hoisting chain or cable breaks.

15 My invention consists in novel features of construction, hereinafter described and claimed.

In order that my invention may be fully understood, I will proceed to describe it with 20 reference to the accompanying drawings, in which—

Figure 1 is a front elevation of the upper part of a cage and adjacent parts, showing my improved clutch mechanism. Fig. 2 is a 25 top plan view thereof. Fig. 3 is a side elevation of the same. Fig. 4 is a detail end view of a central buffer. Fig. 5 is a detail side view of the same, partly in section. Fig. 6 is a perspective view of a corner-pocket. Fig. 30 7 is a perspective view of a clutch-lever frame.

c² shows the shaft-timbers, and n shows the central guide-bars.

c³ is the hoisting chain or rope, connected 35 by chains c⁴ with the cage or lift. Connected with the hoisting chain or rope c³ by means of a short chain c⁵ are ropes c, supporting an upper plate b', lower plate b, and a spring e, compressed between the plates by the weight

40 of the cage or lift on the central supporting-bar d', on which the cage or lift is suspended.

i shows four separate two-armed clutch-levers whose upper ends i' engage with the lower plate, so as to be tripped thereby when the 45 hoisting-chain breaks and unloads the spring and whose lower beveled ends normally rest on stops l, projecting inwardly from the cage-frame. The clutch-levers are pivoted to the upper bars d of the cage or lift by means of 50 rods or shafts p. At the four upper corners of the cage or lift are pockets o, each containing buffers o', of soft elastic rubber, located

over the lower arms k of the clutch-levers and open toward the sides of the shaft. To these pockets o are hinged flaps o², against which 55 the lower arms of the clutch-levers are adapted to come in contact. The bearings of the clutch-levers are so arranged that if the hoisting chain or rope is broken their lower arms describe the segment of a circle upward— 60 that is to say, the ends of the lower arms move from underneath the pockets upward, and therefore of course move outward. In consequence of this they move outside of the cage or lift.

65 o³ shows central pockets each having hinged flaps o⁴ and containing buffers o⁵, of soft elastic rubber, formed with flanges o⁶, adapted to bear on and embrace the guide-bars n. Each pair of clutches arranged on one side 70 are connected with one another by means of a cross-bars of angle shape, the arms of which project upward diagonally from the connecting-points. The tops of these cross-bars are adapted to bear against the flaps o⁴ of the 75 central pockets.

The operation of my improved safety-clutch is as follows: If the hoisting chain or rope breaks, the spring e is released and presses down the lower plate b, so that the four two- 80 armed clutch-levers are rocked, and the lower arms move out of the angle-irons m of the cage or lift and place themselves under the flaps o² of the corner-pockets containing the rubber buffers o'. The bearings for the cushions 85 are sloped off at the bottom, so that there is an equal contact on the whole lower surface of the cushions or buffers. Simultaneously with the rocking of the clutch-levers their lower arms press up the cross-bars, the arms of 90 which come in contact with the flaps o⁴ of the central pockets o³ and press their buffers o⁵ outwardly against the guide-bar n, so that the flanges o⁶ of the buffers embrace the central bar. The guide-bars are so arranged that 95 they offer as large a contact-surface as possible to the central rubber buffers, and the bearing is preferably set so that the contact with the cushions commences at the point of rotation and increases in front, in consequence 100 of which an increased projection of the mass of the pressed buffers results. As all the pockets are only open in front, it is obvious that the buffers can only yield in that direc-

tion. It is also to be noted that the corner-buffers can serve for braking, together with the central cushions, as the rubber presses against the shaft-timbers, or they may be used merely as elastic bearings for the clutch-levers. As the cage or lift slides down farther all the rubber buffers are compressed and are pressed more and more against the sides of the shaft and against the guide-bars, which causes increased friction as the cage or lift moves downward. The central cushions, which, as already mentioned, hold the guide-bars as closely as possible, instantly begin to produce their braking action at the least compression from this part before the speed at which the cage or lift is falling has increased to any extent. When the side buffers are compressed to their maximum point, the lower arms *k* come out of the cage or lift, as indicated in dotted lines in Fig. 1, so far that they rest over the ledges *r*, extending across the shaft-timbers, outside of the shaft. The corner-buffers are preferably arranged so that the clutch-levers when they come into contact with the corner-buffers already project from the cage or lift, and when these rest on the next ledge immediately bear thereon, and as the cage or lift slides farther down they are thrust upward. As at the same time the cushions are more strongly compressed, they act as a still stronger brake on the shaft-timbers.

This clutch mechanism is not only operated by the breaking of the rope, but also by its slipping or jerking, whether the cage or lift is traveling up or down.

As the rubber buffers are readily replaceable, it rests with the person in charge to see

whether they are renewed at the right time and do not become sufficiently worn to render them useless.

Having thus described my invention, the following is what I claim as new therein and desire to secure by Letters Patent:

1. The combination, with a cage or lift of the corner-pockets, the hinged flaps beneath the corner-pockets, the buffers located in the corner-pockets, and the clutch-levers, pivoted to the cage or lift, and having lower arms adapted to bear upwardly against the hinged flaps.

2. The combination, with a cage or lift of the central pockets, the hinged flaps beneath the central pockets, the buffers located in the central pockets, and the clutch-levers pivoted to the cage or lift, having lower arms and an angular cross-bar adapted to bear upwardly against the hinged flaps.

3. The combination, with a cage or lift of the corner-pockets, the hinged flaps beneath the corner-pockets, the buffers located in the corner-pockets, the central pockets, the hinged flaps beneath the central pockets, the buffers located in the central pockets and the clutch-levers pivoted to the cage or lift having lower arms adapted to bear against the flaps of the corner-pockets, and an angular cross-bar adapted to bear upwardly against the hinged flaps.

In witness whereof I subscribe my signature in presence of two witnesses.

RICHARD SCHULZ.
